CLAIM

The ornamental design for a pressurized air delivery console, as shown and described.

DESCRIPTION

FIG. 1 is a perspective view of a pressurized air delivery console showing a first embodiment according to our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is another perspective view;

FIG. 9 is a perspective view of a pressurized air delivery console showing a second embodiment according to our new design;

FIG. 10 is a front view thereof;

FIG. 11 is a rear view thereof;

FIG. 12 is a top view thereof;

FIG. 13 is a bottom view thereof;

FIG. 14 is a left side view thereof;

FIG. 15 is a right side view thereof; and,

FIG. 16 is another perspective view thereof.

The broken lines in the drawings illustrate portions of the pressurized air delivery console that form no part of the claimed design.
